PARAFFIN LIQUEFYING DEVICE

Filed May 4, 1931

UNITED STATES PATENT OFFICE

WILLIAM J. HART, OF SPRINGDALE, ARKANSAS, ASSIGNOR TO HART BROTHERS AND COMPANY, A CORPORATION OF OKLAHOMA

PARAFFIN LIQUEFYING DEVICE

Application filed May 4, 1931. Serial No. 535,023.

My present invention has reference to a paraffin liquefying device for liquefying and removing paraffin from the tubing of a pumping well when pumped, and has for its general object a device for this purpose of a construction designed to simplify and materially improve the paraffin liquefying device upon which I have applied for U. S. patent protection on Sept. 13, 1929, Serial No. 392,403.

The invention will be fully and comprehensively understood from a consideration of the following detailed description when read in connection with the accompanying drawing which forms part of the application, with the understanding, however, that the improvement is capable of extended application and is not confined to the exact showing of the drawing nor to the precise construction described and, therefore, such changes and modifications may be made therefrom as do not affect the spirit of the invention nor exceed the scope thereof as expressed in the appended claim.

25 In the drawing:

Figure 1 is a sectional view through a portion of a well casing showing the device therein.

Figure 2 is a similar view but showing the 30 device in section.

Figure 3 is a sectional view approximately on the line 3—3 of Figure 1.

Figure 4 is a plan view of the disc valve.

Figure 5 is a sectional view through one of the valves and the ejector head.

In the drawing the numeral 1 designates a pipe. The pipe has its upper end screwed in the bore of a head member 2, and in the upper end of the head member there is screwed the upper portion 3 of the tubing, the lower portion of the tubing being screwed to the lower end of the pipe 1. The head 2 is provided with lateral openings which are threaded which communicate with the bore of the head 40 and in each of these angularly disposed openings there is screwed a valve casing 4 that has its inner end provided with a valve seat for a valve 5. The stem of each of the valves 5 has a piston 6 that is adjustably connected to its outer end and influenced by a spring 7 for

moving the piston in one direction in a cylinder 8 that is arranged centrally in the casing 4 and which also influences the valve 5 to seated position. This valve construction is similar to that set forth in my referred to pending application Serial No. 392,403. The pipe 1 is partly surrounded by a tubular sleeve 9, the said sleeve carrying on its lower end a substantially cup-shaped rubber packer 10 which is expandable and which frictionally contacts with the inner end of the well casing 11. The lower end of the tube is held in spaced relation with the pipe 1 through the medium of a spider in the nature of lugs 12 carried by the sleeve 9. The upper end of the sleeve, which terminates only a slight distance away from the lower end of the head 2 is preferably widened and has arranged therein a spider in the nature of lugs 13 which contact with and space the said upper end of the sleeve from the pipe 1. The lugs 13 at their outer edges are flush with the upper end of the sleeve, and with the said upper end of the sleeve provides a rest for a flat disc valve 14.

The packer 10 is provided for dividing the space in the well casing 11 outside the tubing 3, into an upper and a lower part and to act as a seal between the upper and lower parts and any shape or construction of packers 80 which perform this function may be employed.

Steam is introduced into the upper part of the well into the casing 11 and passes down the well, inside of the said casing 11 and 85 around the tubing 3 until it encounters the packer 10. As the packer 10 seals the upper part of the well from the lower part the steam cannot pass the said packer. The result is that pressure is built up in the casing 11 in the 90 upper part of the well, which overcomes the resistance of the spring 7 and opens valve 5, permitting steam and condensed water to pass into the tubing 3. It is to be understood that the well is pumping during this 95 operation and the upward flow of oil caused by the pumping, carries the steam and condensed water along with it. The heat from the steam, the steam and the hot water both inside and outside of the tubing 3 melt the 100

paraffin enough to loosen it so that it is pumped out with the oil. Steam is introduced into the well at timed intervals which depend entirely upon the accumulation of the paraffin.

5 Since water is condensed from the steam introduced into the casing 11 at the top, this water drops until it is stopped by the packer 10. The only outlet for this water is through the valve 5 into the tubing. The valve 5 is above the packer 10 so that water will not pass through the said valve 5 until there is enough water to bring the water level up to the valve. Consequently water always stands 10 above the packer 10 to the height of the valve 5 and this volume of water protects the packer from the live steam. Since the packer 10 seals the upper part of the well from the lower part thereof any pressure existing 15 above the packer will have no effect upon the pressure below the packer and hence the device will not produce any back pressure on the well.

It is to be understood that the steam is introduced into the well for a period of from 25 15 to 20 minutes, once every 12, 24 or 48 hours, depending upon the rapidity of the accumulation of the paraffin. Therefore, most of the 30 time the pressure above and below the packer 10 in the casing is the same. The gas from the well normally passes out of the casing 11 around the tubing 3 and into the gas line. When my improvement is used the gas rises 35 in the casing 11 until it encounters the packer 10. As it cannot pass through the packer it travels through the sleeve 9 where it encounters the disc valve 14. The gas is stopped by the disc valve 14 until it builds up a pressure sufficient to unseat the said valve, and only 40 a small pressure is required to unseat the valve. The gas then passes into the casing 11 above the packer 10. When the well is steamed the steam is introduced into the casing 11 outside of the tubing 3, which tends 45 to build up the pressure in the casing 11. Thus the pressure above the packer 10, plus the weight of the disc valve 14, equals the pressure below the packer 10 so that the disc valve will not open and the well is definitely 50 sealed into an upper and lower part in the casing 11 so that during the steaming process no back pressure is created on the well.

Having described the invention, I claim:

An oil well comprising a casing, a pipe 55 arranged centrally therein, a headed member connected to the pipe and having peripherally spaced inwardly opening spring influenced valves, a tubular sleeve around and spaced from the pipe below the head and secured to the pipe by circumferentially spaced lugs, said sleeve having its upper end arranged in close proximity to the lower end of the head, a disc valve slidable on the pipe for closing the upper end of the sleeve, a member 60 surrounding the lower end of the sleeve and

in frictional contact with the bore of the casing, and dividing the space in the well casing outside of the tube into an upper and a lower part and effecting a seal between such upper and lower parts.

In testimony whereof I affix my signature.

WILLIAM J. HART.
